No. 883,715.

PATENTED APR. 7, 1908.

A. T. HALLOCK.
FIRELESS COOKER.
APPLICATION FILED SEPT. 26, 1907.

UNITED STATES PATENT OFFICE.

ARTHUR T. HALLOCK, OF GRAND RAPIDS, MICHIGAN, ASSIGNOR TO HALLOCK FIRELESS COOKER COMPANY, OF GRAND RAPIDS, MICHIGAN, A CORPORATION OF MICHIGAN.

FIRELESS COOKER.

No. 883,715.

Specification of Letters Patent.

Patented April 7, 1908.

Application filed September 26, 1907. Serial No. 394,726.

To all whom it may concern:

Be it known that I, ARTHUR T. HALLOCK, citizen of the United States, residing at Grand Rapids, county of Kent, and State of Michigan, have invented certain new and useful Improvements in Fireless Cookers, of which the following is a specification, reference being had therein to the accompanying drawing.

10 This invention relates to a fireless cooker, and particularly to a structure wherein the cooking receptacle is packed in nonconducting material.

15 The invention has for an object to provide a novel and improved construction of the case in which the cooking receptacle is disposed, and also of the covering for the packing material therein.

20 A further object of the invention is to provide a novel construction of the cover for the cooking receptacle by which the same is rendered nonconductive and preserved against injury from the expansion and contraction of the material thereof.

25 Other and further objects and advantages of the invention will be hereinafter fully set forth and the novel features thereof defined by the appended claims.

Referring to the drawing:—Figure 1 is a perspective of the invention; Fig. 2 is a longitudinal section on the line 2—2, Fig. 1; Fig. 3 is a vertical section on the line 3—3, Fig. 1; Fig. 4 is a detail sectional perspective of the cover for the cooking receptacle; Fig. 5 is a similar view of the frame for holding the cover for the packing material, and Fig. 6 is a detail perspective of the cover plate for the cooking receptacle.

Like numerals refer to like parts in the 40 several figures of the drawing.

The numeral 10 designates the body of the receptacle which may be of any desired construction or configuration, and in the present instance comprises a box or casing 45 having the central partition 11 and provided with roller casters 12 by which it may be conveniently moved. This casing has hinged thereto at the rear the cover 13 which is provided with fastening devices 14 adapted 50 to coöperate with similar devices 15 upon the casing 10. The angles of this casing are mortised into each other to provide a tight joint and a series of corner blocks 16, as shown in Fig. 2, are provided at each of the 55 angles, the upper block of the series within

the casing providing a shoulder upon which the frame 17 rests. This frame is provided with a fabric covering 18 which protects and incloses the nonconducting material 20 forming the packing for the receptacle 20 disposed within the casing. 60

It has been found that when long corner blocks are used, the wood does not expand endwise but transversely thus causing the sides and ends of the casing to swell and break loose from the corner block, and this difficulty is overcome by the use of a series of spaced blocks in the corners of the casing. The casing is also provided with a series of corner irons 21 which coöperate with the blocks at that point and permit the block to be used as a socket for the caster 12 inserted therein. 65

The packing 20 may be of any desired material, but it has been found that excelsior packing is preferable for this purpose as it does not become sour or mildewed as is the case with hay and straw, and when pressed into the casing retains its position so that the lining can be removed without disturbing the 70 packing. By mounting the lining upon a removable frame it can be removed for washing or renewal and readily replaced in position thus rendering it entirely sanitary. Extending between the partition 11 and a similar partition 22 in the cover is a toggle joint 75 23 comprising the opposite members pivoted to each partition and to each other. When the cover is closed these members are adapted to seat in a recess 24 in the partition 22 and a similar recess 25 in the partition 11. The cover is provided with a frame 26 similar to the frame 17 and having a fabric covering 27 which is applied to the lid members and secured therein by means of the fastening 80 devices 28 extending through the side edge of the cover as shown in Figs. 1 and 3 and engage the frame therein. This cover is formed of a series of panels 29, as shown in Figs. 2 and 3, these being inserted and secured in the frame 30 of the cover so as to prevent the expansion and contraction which 85 ordinarily occurs in connection with a solid cover piece. The meeting faces of the casing and cover have thereon a felt packing 50 to 90 retain the heat. 95

The receptacles 31 disposed within the packed casing are adapted to receive any desired cooking vessel, for instance, as indicated by dotted lines in Fig. 3, these being 100 110

supported above the bottom of the receptacle by a rack 32 for that purpose, and the vessel is closed by a nonconducting cover 33. This cover is provided with the flanged portion 34 and a central depressed body 35 which contains packing 36 of nonconducting material above which, if desired, a block 37 is inserted, while the top plate 38 thereof is provided with the transversely extended dovetailed groove in which a similarly depressed strip 39 is inserted with the grain thereof disposed at an angle to the grain of the cover. From this strip attaching pieces 40 extend and are bent downward over the flange 34 to retain the packed plate in position within the receptacle cover. Under some conditions it may be desired to cook the articles within the cooking receptacle in a bag and this may be effected by attaching the bag to the periphery of this receptacle cover, as indicated by dotted lines at 41 in Fig. 2.

Each of the cooking receptacles is provided at opposite sides with lifting handles 42 and these are adapted to receive the handles 43 which are temporarily connected to the eyes 44 carried by the ends of the casing. The U-shaped ends 45 of these handles may be readily detached from the eyes and connected to either of the receptacles within the casing for the purpose of lifting the same therefrom when it is in a heated condition. The covers for the receptacles are also provided with the lifting eye 46, as shown in Fig. 1.

The rack 32 supporting the cooking vessel is composed of an annular strip 47 of sheet material through which the cross wires 48 extend diametrically at substantially the mid width thereof and beyond the strip 47 so as to contact with the inner side of the receptacle within which it is disposed, while the strip 47 retains the cooking vessel in its central position upon the rack and prevents sidewise slipping thereof within the receptacle when the same is being conveyed to or from the chest. Under ordinary conditions the cooking is effected within the receptacle, but for some uses the cooking vessel 31 may be placed within the receptacle which may contain a body of hot water and for that purpose the rack hereinbefore described is used.

In the operation of the invention the cooking vessel is placed within the packed receptacle and the top of the casing closed so as to retain the heat and continue the cooking operation as is usual in this class of inventions. Under such conditions it is important that the cover of the receptacle containing the cooking vessel should be thoroughly insulated against a reduction of temperature when the lid is opened for the purpose of removing the cooking receptacle from the receptacle in the casing. For this purpose the lid of the receptacle is packed, as shown in

Figs. 2 and 4, and in order to prevent the warping and expansion of the wooden plate which holds the packing in position a cross strip is provided having the grain running in the opposite direction to that of the disk or cover plate thus preventing any warping or splitting thereof, and this disk is secured to the metal cover by means of the attaching pieces extended therefrom. This construction permits the removal and replacing of the nonconducting material within the cover. The containing receptacle is provided with the ears adapted to receive the handles which may also be applied to the casing as when removed no obstruction is present at the top of the receptacles.

A further object of the invention is to provide a removable lining for the packing material mounted on a frame which may be readily withdrawn from the casing and the cloth thereof washed and returned without disturbing the packing material which is particularly desirable as this lining frequently becomes soiled from cooking material spilled thereon, thus rendering the cooker sanitary in use and dispensing with the separate packing cushions heretofore used at the cover of the casing.

Having described my invention and set forth its merits, what I claim and desire to secure by Letters Patent is:—

1. In a fireless cooker, a casing provided with a pivotally mounted cover, packing material within said cover and casing, removable retaining frames inserted within the cover and casing, and a lining for the packing supported by said frames.

2. In a fireless cooker, a casing provided with a pivotally mounted cover, packing material within said casing and cover, removable retaining frames inserted within the cover and casing, a lining for the packing supported by said frames, and a series of securing devices extending inward from the outer face of the casing and cover to engage the lining supporting frames.

3. In a fireless cooker, a packed casing, a receptacle disposed therein, a downwardly projecting lid for said receptacle provided with a nonconducting packing therein, a cover plate for said packing having a strip inserted across the diameter thereof, and attaching pieces extending from said cover to said lid.

4. In a fireless cooker, a packed casing, a receptacle disposed therein, a downwardly projecting lid for said receptacle provided with a nonconducting packing therein, a cover plate for said packing having a strip inserted across the diameter thereof, and attaching pieces secured at one end to said strip and bent at their free ends to embrace the flange of said lid.

5. In a fireless cooker, a packed casing, a receptacle disposed therein, and a support

rack within said receptacle comprising an annular band having transversely extending supporting wires disposed between the edges thereof and extended beyond the outer face 5 of said band.

6. In a fireless cooker, a rectangular casing provided with a pivoted cover, spaced corner blocks at the intersection of the walls of said casing, a packing disposed in said casing, a 10 removable frame inserted within the casing a lining for said packing mounted upon a frame, and means for removably retaining said frame in position.

7. In a fireless cooker, a packed casing, a receptacle disposed therein, a lid for said receptacle provided with a nonconducting packing, a cover plate for said packing having a strip dovetailed into the material of the plate and extended across the same and means for securing said plate to the lid. 15

In testimony whereof I affix my signature in presence of two witnesses.

ARTHUR T. HALLOCK.
